Term of patent 14 years

(Cl. D14—3)

FIG. 1

FIG. 3

— E I C — 4

FIG. 1 is a rear perspective view of a combined tent and trailer showing my new design;

FIG. 2 is a front perspective view thereof;

FIG. 3 is a front perspective view in a collapsed position; and

FIG. 4 is a side elevational view showing the collapsible portion in raised position.

The cross hatching in FIGS. 1 and 2, representing fabric, is understood to cover the entire area indicated.

The dominant features of my design reside in the portions shown in full lines.

I claim:

The ornamental design for a combined tent and trailer, as shown and described.
